CLAIM

The ornamental design for a connection of electric cleaning brush and cover set, as shown and described.

DESCRIPTION

FIG. 1 is a front perspective view of a connection of electric cleaning brush and cover set showing my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof; and,

FIG. 8 is a rear perspective view thereof.

The broken lines in the drawings illustrate environment only and form no part of the claimed design.

1 Claim, 8 Drawing Sheets
